UNITED STATES PATENT OFFICE.

FERDINAND SCHAUB, OF JERSEY CITY, NEW JERSEY.

INSULATOR.

1,178,539.

Specification of Letters Patent.

Patented Apr. 11, 1916.

Application filed December 14, 1911. Serial No. 665,674.

To all whom it may concern:

Be it known that I, FERDINAND SCHAUB, a citizen of the United States, residing at Jersey City, in the county of Hudson and State of New Jersey, have invented certain new and useful Improvements in Insulators, of which the following is a full, clear, and exact specification.

This invention relates to insulators and 10 has for an object to provide an improved cleat for spacing apart and holding in proper relative positions electric wires.

The invention particularly relates to a cleat made up of a pair of similar and interchangeable half-cleats, each of which contains a pair of spaced-apart wire-seats which, for convenience, may be termed half-wire-seats. In the illustrated form of the invention the half-wire-seats in each half-cleat differ one from the other and each half-seat is located in position and formed for mating with the dissimilar seat in the other half-cleat when two of these are assembled.

The invention also contemplates the use 25 in a cleat made up of a pair of cleat-members or half-cleats and having a pair of wire-wedging-seats, each of which half-cleats will have a wire-seat and an adjacent wedge, and a wire-seat and an adjacent wedge-seat.

The interlocking of the half-cleats prevents independent movement on the plane of cleavage.

In the drawings accompanying and forming 35 a part of this specification a practicable embodiment of the invention is illustrated wherein—

Figure 1 is an elevation of a cleat made up of a pair of assembled similar, interchangeable half-cleats. Fig. 2 is a plan view of what will either be the top of the upper cleat or the bottom of the lower cleat. Fig. 3 is a plan view of the meeting face of one of the half-cleats. Fig. 4 is a similar view 40 with the ends reversed and showing the relation in which the cleats will assemble one with the other. Fig. 5 is an elevation of one of the half-cleats. Fig. 6 is a longitudinal view of a pair of assembled half-cleats held 45 in position on some suitable support by means of screws; and Fig. 7 is a cross-sectional view taken at about the plane indicated by the line 7—7 of Fig. 1.

Since the invention contemplates the use 50 of a pair of half-cleats similar in form and interchangeable, one of these cleats by itself

will first be described. The cleat illustrated comprises an elongated body portion 10, made, for instance, of porcelain, and having at each end a half-wire-seat. At one end it 55 is provided with a seat 11, having a concave surface, this seat curving inward relatively to the body and outward relatively to the end, and lying wholly within the edges of the meeting face of the body. Adjacent the half-wire-seat 11, is shown a boss 12, provided with a wedge-face 13, which merges into the wall of the wire-seat 11. At the other end of the body is a wire-seat 14, which curves outward relatively to the 60 end and outward in the center relatively to the body, the surface of this seat being convex. This wire-seat passes through the side-face 15, of the cleat body. The flanges 110 at the ends of the seat 11, serve to pass the 65 wire into the portions of the seat 14, at the face 15, of the body. It will be noticed, particularly by reference to Figs. 1 and 5, that the center of the wire-seat 14, where it extends through the face 15, is on a line 70 with the meeting-face 16, at the other end of the cleat adjacent the wire-seat 11. This is for the purpose of bringing the two wires held by the cleat into parallelism. It will also be noticed that the cleat-half is thicker 75 at one end (the end carrying the seat 14), than it is at the other end (the end carrying the seat 11). When the half-cleats are assembled they interlock in such manner that 80 independent movement on the plane of 85 cleavage is prevented.

The cleat is provided with a pair of holes 17, through which screws will be passed for holding a pair of these cleat-halves in assembled position. Suitable screws 18, are 90 illustrated in Fig. 6, which will hold the halves together and against some suitable surface. The boss 12 will be accommodated by a socket 19, adjacent the seat 14, which socket may for convenience be termed a 95 wedge-seat. The screw-holes in the present instance are shown passing respectively through the center of the boss 12 and the socket 19. The screw-holes are counter-sunk. Adjacent the counter-sinking is a raised 100 ring or flange 20 which will hold the body portion of the cleat from surface engagement with the surface upon which the cleat is mounted for preventing breakage when the screws are tightened. When the cleat 105 halves are assembled, the wire-seat (which may be termed a half-seat 11), will coöper-

ate with the wire-seat 14 (which may be termed a half-seat) in another cleat member, and thereby form a wire-seat so that a complete wire-seat will be formed at each end 5 of the cleat by the mating of a pair of dissimilar wire-seats or half-seats. Each half-cleat is so formed that it will interchangeably mate with a similarly formed cleat, but only in one certain relative position. The dissimilar ends must be together. The pair 10 of cleat members will then mate and form a pair of similar, spaced-apart wire-seats.

In stringing the wire, the wires will be placed preferably in the seats 14, the cleats assembled, and by means of the wedging action of the wedge-faces 13, and the configuration of the seats 11 and 14 the wires will be bent in both a vertical and a horizontal plane resulting in a compound bend, which will produce a kink for preventing the wire from reeving through the wire-seats. Owing to the bending of the wire in the seats, in the present instance the double kinking of the wire, the pressure required to prevent its reeving is less than in existing forms of cleats, so that the strain on the porcelains is greatly lessened and they may be held together by a comparatively slight pressure of the screws 17. This being the case, the breakage in installing and in the use of the cleats is minimized.

35 Although but one practicable embodiment of my invention is illustrated and in that embodiment a pair of seats is shown, it will be apparent that changes may be made within the scope of the claims without departing from the spirit of my invention.

Having thus described my invention, I claim:

- 40 1. An insulator, comprising a pair of complementary elongated sections, each formed with a pair of spaced-apart curved wire-receiving grooves and a tapered centering and expanding plug positioned adjacent one of said grooves and having a curved wire-engaging surface concentric therewith, and a complementary countersink 45 adjacent the other of said grooves to receive the tapered expanding plug of the ad-

Copies of this patent may be obtained for five cents each, by addressing the "Commissioner of Patents, Washington, D. C."

50 adjacent section, each groove and co-operating expanding plug co-acting to kink and clamp a wire with a wedging action in a direction at right angles to the axis of the plug and in a plane parallel thereto.

2. An insulator, comprising a pair of complementary elongated sections, each formed with a pair of spaced-apart curved wire-receiving grooves and a tapered centering and expanding plug positioned adjacent one of said grooves and having a curved wire-engaging surface concentric therewith, and a complementary countersink adjacent the other of said grooves to receive the tapered expanding plug of the adjacent section, each groove and coöperating expanding plug coacting to kink and clamp a wire with a wedging action in a direction at right angles to the axis of the plug and in a plane parallel thereto, the registry of said expanding plugs and countersinks preventing individual movement of the sections at the plane of cleavage. 55 60 65 70

3. An insulator, comprising a pair of complementary elongated sections, each formed with a pair of spaced-apart curved wire-receiving grooves, and a bored tapered centering and expanding plug positioned adjacent one of said grooves and having a curved wire-engaging surface concentric therewith, and a complementary board countersink adjacent the other of said grooves to receive the tapered expanding plug of the adjacent section, and a securing screw positioned in the bores formed within said plugs and countersinks whereby each groove and co-operating expanding plug will coact to kink and clamp a wire with a wedging action in a direction at right angles to the axis of the plug and in a plane parallel thereto upon the seating of said screws in a suitable support. 75 80 85 90

In witness whereof I have hereunto set my hand in the presence of two subscribing witnesses.

FERDINAND SCHAUB.
